CLAIM

The ornamental design for a rotisserie motor or the like,
as shown.

DESCRIPTION

FIG. 1 is a perspective view showing one side and a
part of the top of my design for a rotisserie motor or the
like;

FIG. 2 is a perspective view showing the bottom and a
part of one side of my design;

FIG. 3 is a top plan showing my design; and

FIG. 4 is a side elevation showing my design.
